UNITED STATES PATENT OFFICE.

EDWARD FISHER GOBEN, OF MUSKOGEE, OKLAHOMA.

SPIKE-PULLER.

1,223,269.

Specification of Letters Patent. Patented Apr. 17, 1917.

Application filed July 25, 1916. Serial No. 111,287.

To all whom it may concern:

Be it known that I, EDWARD F. GOBEN, a citizen of the United States, residing at Muskogee, in the county of Muskogee and State of Oklahoma, have invented new and useful Improvements in Spike-Pullers, of which the following is a specification.

This invention relates to spike pullers and consists of an improvement on or continuation of the construction and arrangement of the spike puller embodied in my pending application Serial No. 73,692, filed January 22, 1916, and allowed March 28, 1916.

The primary object of the improvement is to brace the movable jaw and provide the same with a reversible bit so that when one end of the bit becomes broken or dulled it may be reversed to bring the opposite spike engaging end into operative position relatively to a spike, a number of these bits being supplied with each puller so that the practical service of the device as a whole may be prolonged without requiring repair. A further object of the present invention is to provide a movable jaw which in the main is constructed of a metal of a lower grade than the fixed jaw and to provide said movable jaw with a reversible bit of high grade metal or a metal harder than the movable jaw and whereby the movable jaw in the main will not become in the least impaired and all the wear imposed upon the reversible bit, which may be readily changed to bring opposite ends thereof into operative position relatively to a spike to be pulled and to coact with the fixed jaw.

With these and other objects and advantages in view the invention consists in the construction and arrangement of the several parts which will be more fully hereinafter described and claimed.

In the drawing:

Figure 1 is a perspective view of a spike puller embodying the features of the invention and broken away in part.

Fig. 2 is a front elevation of the puller shown applied to a rail and in operative position to draw a spike, the puller being illustrated in full and dotted lines to show the manner of applying the same and also the operation thereof.

Fig. 3 is a transverse vertical section through the rail and a portion of the tie as shown by Fig. 2 and illustrating the improved spike puller in applied position and in edge elevation.

Fig. 4 is a detail perspective view of the reversible bit constituting one of the features of the improvement.

The numeral 5 designates the support of the device which also constitutes the operating means and consists of a flat plate of considerable strength and durability which is mainly of circular contour and provided at one extremity with a tapered fulcrum extension 6 having a lower convex edge 7; and at the opposite extremity the plate has an approximately rectangular extension 8 terminating in a shoulder 9 which extends full length thereof in a vertical direction. The upper edge of the extension serves as a tapping means 10, the said edge being straight and reinforced or thickened in part by the shoulder or stop brace 9 formed at the end of the extension 8. The lower edge of the support or body 5 in advance of the adjacent lower edge 7 of the fulcrum extension 6 is adapted to be formed with a series of teeth or serrations 11, the said lower edge with its teeth constituting the primal fulcrum 80 for the complete device in view of the fact that the said edge is below the lower edge 7 of the extension, the said lower edge of the support or body 5 being indicated as a whole by the numeral 12. In advance of the teeth or serrations 11 a spike head clearing recess 13 is formed in the extension 8, and on the outer side of the support or body against the shoulder or stop brace 9 a fixed jaw 14 is secured by bolts 15 arranged as shown. 90 On the same side of the support or body is a movable jaw 16 which is continuous with or forms a part of an elongated handle or rein 17, this movable jaw with its handle or rein constituting the main operating lever. 95 The movable jaw 16 is fulcrumed near the lower end, as at 18, and engaging this fulcrum and secured to the support or body 5 is a brace or strengthening device 19 which tends to reinforce the fulcrum and the jaw 16 and sets up considerable resistance to strain or breakage when the main operating lever including the jaw 16 and the handle or rein 17 is actuated to draw or pull a spike. 100 The main operating lever, including the jaw 16 and handle or rein 17, has a prying action relatively to a spike and effects a rocking movement of the support or body 5 when drawing or pulling a spike. The jaw 16 at the point where the end of the brace 19 engages the fulcrum 18 is formed with a recess 110 20 so as to permit the jaw to work under or

have a clearance relatively to the said brace, and the remaining part of this jaw is thickened or strengthened by the addition of metal, especially at the lower end. The fixed jaw 14 is removably mounted in connection with the extension 8 and has a lower inwardly inclined toe 21 which projects below the lower edge of the extension close to the recess 13, the toe being given a clearance to engage one side of the spike head by means of a recess 22 formed in the inner edge thereof adjacent to the toe.

One of the main features of the improvement is a reversible bit 23 removably secured by bolts 24 to the edge of the jaw 16 opposed to the edge of the jaw 14, said bit 23 being of materially harder metal than the jaw 16 and having toes 25 formed at opposite ends and whereby the bit may be released and reversed in the event of breakage of the toe 25 that may have been coöperating with the toe 21 of the fixed jaw 14. The lower extremity of the movable jaw 16 with a portion of the reversible bit projects below the lower edge of the support or body 5 and the toes of the bit and fixed jaw are in reverse position as shown so as to positively engage opposite sides or portions of a spike below the head of the latter when the puller is set in position for drawing a spike.

As hereinbefore specified, the support or body 5 is of plate form or flat and the inner side thereof, or the side that comes next to the rail, is without projection or broken structure of any character so that the inner side of the support or body 5 may be brought into close movable contact with the outer edge portion of the head or ball of a rail to brace the puller as a whole during the operation of pulling or drawing a spike. In applying the improved device to a spike it is first arranged as shown by dotted lines in Fig. 2 with the toes 21 and 25 of the fixed jaw and the bit respectively closely impinging against the opposite sides of the spike immediately under the head of the latter, and when in this position the lower teeth 11 will bear upon the outer portion of the rail flange and the device will be pushed inwardly far enough relatively to the rail to cause the inner smooth or unbroken side of the support or body 5 to snugly engage the outer edge of the head or ball of the rail. The operator then pulls the device toward him by means of the handle or rein 17 and this tension on the handle or rein causes a tight bite of the toes 21 and 25 on the head of the spike and at the same time the support or body 5 turns or rocks in the direction of the pull, the teeth or serrations 11 at the lower edge of the support or body 5 preventing the puller from slipping. The lower primal fulcrum edge 12 first engaging the flange of the rail will cause a strong leverage 85 to be exerted on the spike to start the same,

and by continuing the pull on the handle or rein 17 the lower edge 7 of the fulcrum extension 6 will eventually engage the flange of the rail at a time when the spike will have been sufficiently loosened to permit a ready and complete withdrawal thereof by continuing the movement of the support or body 5 on the fulcrum extension 6. During this movement of the support or body 5 a material bracing action will ensue by reason of the engagement of the inner side of the support or body 5 with the outer edge of the head or ball of the rail, and it will be seen that by this bracing engagement of the support or body with the rail head or ball the device is held in place and is materially strengthened, especially when the pull on the device is exerted in a slight inward lateral direction. When the spike head is somewhat embedded in the tie the toes 21 and 25 may be driven thereunder by tapping on the upper edge of the extension 8 with a hammer or other implement so as to effectively seat the said toes relatively to the spike head or cause the toes to be depressed into the tie. By means of the operation of the puller parallel with the rail and the general construction of the device as hereinbefore described, spikes can be extracted close up between frogs and on bridges where the use of ordinary spike pullers is impracticable.

In view of the bracing of the fixed jaw 14 the said jaw will be greatly strengthened in its operation, and, moreover, by the use of the reversible bit the service of the device 100 may be prolonged, it being proposed to provide with each spike puller a number of these bits so that a bit that may have become completely broken or unfit for further use may be readily replaced without material 105 delay.

The foregoing construction presents many advantages, especially from operative and commercial standpoints. In addition to the ready removal and reversal of the bit 23, the jaw 14, which is also a bit, may be readily removed and replaced by a similar device in the event of breakage, or when the toe 21 thereof becomes dulled the said jaw or bit 14 may be preserved in operative condition by sharpening the toe. The shoulder 9 against which the jaw or bit 14 is braced operates to materially relieve the bolts 15 of strain and tendency to breakage. It is also proposed to supply a number of bits similar 110 to the bits 14 and 23 with each puller and by this means the bit 14 may be readily replaced without impairing the remaining structure of the puller or requiring the same to be sent back to the factory or shop for 120 repair, and in like manner the bit 23 after it has been reversed and considerably worn by usage at both ends, or in case both toes 25 become dulled, may be replaced by another bit with sharp toes without waiting 130

to sharpen the dulled toes of the bit 23 that has been in use. The bits 14 and 23 will be preferably formed of a higher grade metal than the remaining parts of the puller and the cost of manufacture of the entire device may thus be materially reduced without affecting its necessary strength and durability. Another advantageous structural feature is that the lower end of the bit 23 is coincident with the lower end of the jaw 16 forming part of the lever 17, and by this means the bolts 24 are materially relieved of strain during the operation of the said lever and bit. Both bits 14 and 23 are prevented from moving or having the least shifting action when subjected to strain in removing a spike. This positive retention of the bits and their reinforcement by the parts to which they are applied to relieve the fastenings therefor of strain, together with the reinforcing and strengthening action of the brace 19 relatively to the jaw 16 and particularly the fulcrum bolt 18 of the latter jaw, are features which conjointly contribute to the production of a strong and durable as well as a conveniently operable spike puller.

What is claimed is:

1. In a spike puller, a flat support having a lower curved edge forming a primal fulcrum edge and a rear extension providing an additional fulcrum means, the support at its forward extremity having a vertically extending shoulder at an angle thereto, a fixed jaw removably applied to the outer side of the support against the shoulder and having a lower extremity with a toe depending below the lower edge of the support, a pivoted jaw also having an end depending below the lower edge of the support and continuing into an elongated handle forming a prying lever for operating the complete device, and a reversible bit with a toe at each end removably secured to the lower portion of the front edge of the pivoted jaw to coact with the fixed jaw, the said reversible bit when applied having its lower terminal coincident with the lower end of the pivoted jaw to brace the bit.
2. In a spike puller, a flat support having lower fulcrum means and a vertical shoulder at an angle to the front extremity thereof and projecting outwardly beyond the outer side of the support, a fixed jaw applied to the outer side of the support against said shoulder and terminating at its upper end flush
3. In a spike puller, a flat support having a lower fulcrum means, a fixed jaw applied to the outer side of the support and having a lower depending end with a toe, a pivoted jaw on the support continuing into an elongated handle forming a prying lever, and a reversible bit secured to the front edge of the pivoted jaw adjacent to the fixed jaw and provided with a toe at each end to coöperate with the toe of the fixed jaw.
4. In a spike puller, a flat support having lower fulcrum means and an extension provided with a vertical bracing shoulder at an outward angle to the outer side of the support, a fixed jaw removably applied to the outer side of the support against said shoulder and having a lower depending toe, and a pivoted jaw on the outer side of the support continuing into an elongated handle forming a prying lever and provided with a depending toe to coöperate with the toe of the fixed jaw.
5. In a spike puller, a flat support having lower primal and additional fulcrum edges and an extension provided with a vertical bracing shoulder on the outer side of the support, a fixed jaw applied to the outer side of the support against said shoulder and having a lower depending toe, a pivoted jaw on the outer side of the support continuing into an elongated handle forming a prying lever and having a toe to coöperate with the toe of the fixed jaw, and a brace secured to the outer side of the support and extending over and having one end engaging the pivot of the pivoted jaw.

In testimony whereof I have hereunto set my hand in presence of two subscribing witnesses.

, EDWARD FISHER GOBEN.
